UNITED STATES PATENT OFFICE.

CARL G. KOPPITZ, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

FIELD-MAGNET FRAME.

1,327,619.

Specification of Letters Patent. Patented Jan. 13, 1920.

Application filed July 14, 1917. Serial No. 180,644.

To all whom it may concern:

Be it known that I, CARL G. KOPPITZ, a citizen of the United States, residing at Greensburg, in the county of Westmoreland and State of Pennsylvania, have invented 5 certain new and useful Improvements in Field-Magnet Frames, of which the following is a specification.

The present invention relates to field magnet frames in an electric machine.

It is the special object of my invention to produce a field structure for electric motors of exceedingly small size in a simple and compact form, of a single piece of material 15 and so cheaply that the cost of manufacture is merely nominal.

Reference is had to the appended drawing in which—

Figure 1 is a longitudinal section, and 20 Fig. 2 a transverse section through the field structure constituting my invention.

In the drawing 1 is a tubular body of wrought iron or steel and 2 and 3 are pole pieces projecting toward the interior of the tube. The pole pieces 2 and 3 are integral 25 with the tube and are formed thereon by rolling, drawing or depressing the material of the tube. 4 and 5 represent conventional field coils, 6 the armature, 7 the commutator

and 8 the armature wires connected to the 30 commutator. 9 and 10 are bearing blocks for the armature shaft 11. In the bearing block 10 are openings for accommodating the support for the brushes and their terminals.

35

By selecting the process of rolling, drawing or depressing, which is well understood in itself, in contradistinction to other processes, such as casting, I can reduce the time and cost of manufacture to a minimum. 40 The separate lengths of tube required may be cut from long tubes or pipes in a very short time and in large quantities and are pressed or rolled in a single operation.

45

I claim:

1. The process of making a field magnet frame which consists in depressing portions of tubing to form polar projections thereon.

2. A field magnet frame consisting of pressed tubing having portions depressed 50 into shape to fit an armature and form polar projections.

In testimony whereof I affix my signature in presence of two witnesses.

CARL G. KOPPITZ.
